VALVE STRUCTURE

Edgar D. Flintermann, Detroit, Mich., assignor to
Michigan Steel Casting Co.

Application May 18, 1931, Serial No. 538,100

2 Claims. (Cl. 126—285)

This invention relates to closure structures for furnaces and it has particular relation to the provision of a gate or valve structure for controlling the flow of gases to or from furnaces.

5 The invention has for its main objects the provision of a gate structure of the above indicated character which is relatively simple, durable and which may be manufactured at a minimum of expense; the provision of a gate structure which 10 does not readily warp and distort; the provision of a gate structure which constitutes a particularly effective barrier to the flow of hot gases; the provision of a sectional gate structure from which defective units may be removed and replaced at 15 a minimum expense and with a minimum of lost time.

Heretofore in the construction of furnaces, particularly those of the open hearth type, or similar types, in which a duct or conduit termed a flue 20 has been provided for conducting away the hot gases, it has been customary to provide a suitable gate or valve structure for regulating the flow of gases to suit particular conditions of operation. Since these spent gases as they emerge from the 25 furnace are heated to a relatively high temperature, it has been considered necessary to provide a cooling system for conducting away the heat transferred to the gate or valve from the gases. For this purpose, it has heretofore been 30 customary to provide hollow chambers in the gate and to connect these chambers by means of a conduit to a suitable source of cooling fluid. Obviously, such construction was complicated and expensive to manufacture. Furthermore, the presence of 35 the relatively cool gate or valve in proximity to the interior of the furnace resulted in excessive radiation of heat and a resultant lowering of the efficiency of the furnace as a whole. Also, the circulation system employed for conducting the 40 cooling fluid was likely to fail at critical moments, causing delay and loss in the operation of the furnace.

The present invention relates to valve structure which is composed of a relatively large number of units, the exposed ones of which are composed of a heat resistant alloy. These units are so arranged with respect to each other that distortion due to relatively high temperatures is 45 minimized. Where a structure of this character is employed the use of a cooling system with the resultant expense, trouble and lowering efficiency of the furnace is obviated. For a better understanding of the invention reference may now be 50 had to the accompanying drawing, in which:

Fig. 1 is a front elevational view of a gate or valve constructed in accordance with the provisions of the invention;

Fig. 2 is a fragmentary view showing one of the units of the valve structure together with

the connections for attaching it to adjacent units:

Fig. 3 is a fragmentary cross sectional view showing on a larger scale the connection or joint between units of the gate;

Fig. 4 is a fragmentary cross sectional view showing on a larger scale, a device for preventing longitudinal displacement of different sections of the gate with respect to each other;

Fig. 5 is a fragmentary cross sectional view of 10 a slightly different form of device for preventing longitudinal displacement of different sections;

Fig. 6 is a fragmentary cross sectional view of 15 a furnace flue showing the improved gate structure in position, and

Fig. 7 is an enlarged fragmentary cross sectional view taken along the line 7—7 in Fig. 6.

In practicing the invention, a furnace flue 10 of conventional design is provided with guides 12 at either side disposed at a slight angle with 20 respect to the vertical for a purpose which is presently to be described. A suitable valve or gate structure 14 is slidably disposed for reciprocation within these guides and may be operated by means of a rod 16 which is attached thereto 25 and which may be operated by means of suitable mechanism (not shown). The gate 10 is provided with an upper section 18 of trapezoidal contour which, since it is not exposed to high 30 temperatures, may be formed of cast iron or other ordinary metal. The upper portion of this section may be provided with a marginal flange 20 which is bored at or near the center line of the gate to receive the lower end of the operating rod 16. The rod may be held in position 35 within the opening by means of upper and lower nuts 22 and 24 in a conventional manner.

As shown in Figs. 2, 3 and 5, the lower edge of the section 18 is provided with a pair of flanges 26 extending outwardly, downwardly and then 40 inwardly to define a T-shaped groove 27, which extends the entire width of the section, the outer edges or sides of flanges 26 being disposed in the same plane as the edges of the flange 20. The groove 27 is adapted to receive a T flange 28 45 formed along the upper margin of an intermediate section 30, thus providing a flexible connection between the two. This section is provided with flanges or ribs 32 and 34 upon opposite sides thereof which are disposed slightly below the T flange 28 in position partially to protect the flanges 26 from the direct blast of hot gases, and which are of the same cross sectional width as the flanges 20 and 26. The section is 50 also provided with end flanges 36 and 38 of the same cross sectional width as the flanges 34 and 32. These flanges extend downwardly from the flanges 32 and 34 and are integrally formed with other flanges 40 along the lower margin of the 55 60

section which are identical in construction with the flanges 26.

As many intermediate sections 30, all of which have grooves at one edge (preferably the lower) 5 mating with corresponding T flanges upon the edge of the adjacent section, as may be desired may be secured together by sliding the T flanges 28 of one member within the corresponding grooves 27 of the adjacent member in order to 10 form a gate or valve of any desired height. It is, of course, to be understood that the lowermost section of the gate may be provided along its bottom edge with a simple flange 42 corresponding to the marginal flanges 20 and 38 in 15 the upper section 18 and the intermediate section 30. By adopting this construction for the lower section, a slightly simplified and less expensive structure is obtained.

In order to obviate longitudinal displacement 20 of the flanges 28 within the grooves 27 mating lugs 44 and 46 may be formed upon a flange 26 and the corresponding flange 32 respectively. These lugs are formed with openings 48 within 25 which a key pin 50 of L shape may be dropped, thus positively securing the sections together against relative movement laterally of the valve.

In the form of the invention shown in Fig. 5, the flanges 26 are provided with transversely extending openings 52 which are disposed in 30 axial alignment with respect to notches 54 formed in the upper edges of the T flanges 28. The openings together with the notch receive a transversely extending bolt 56 which may be 35 maintained in position by means of a conventional nut 58.

In the construction of a gate in accordance 40 with the principles of the invention the T flange 28 of the first intermediate section is slid longitudinally into the groove 27 and is secured in position either by means of a pin 50 within openings in lugs 44 and 46 or by means of a through bolt 56. As many sections as may be desired are thus secured together to form a gate or valve which is composed of relatively movable units. 45 The assembled structure is then slid within the guides 12 and lowered by means of supporting rod 16 to the desired position in order to obtain the requisite flow of gases through the flue. When the gate is open or partially closed and is 50 suspended from the rod 16, the lower edges of the T flanges 28 contact with the lower inner surfaces of the grooves 27 and thus provide a substantially gas tight seal. Similarly, if the gate is completely closed, so that the weight is 55 borne upon the lower section, a seal is effected by contact of the upper face of the T flange 28 with the upper inner face of the groove 27, or by contact of the lower edges of the flanges 26 with the upper faces of flanges 32-34, or contact is 60 made at both points simultaneously.

Since the flanges 20, 38, 36, 34, 32 and 26 all 65 extend outwardly equal distances from the plane of the section composing the valve, it is manifest that an effective seal is formed between the margins of the gate and the side walls of the channel. The effectiveness of this seal is increased by reason of the fact that the guides 12 are inclined as shown in Fig. 6 in such manner that the flanges upon one side of the valve are 70 maintained positively in contact with the lower side wall of the guides 12 under the urge of gravity.

All of the intermediate sections 30 and the bottom section 32 of the valve are composed preferably of a heat resistant alloy such as chrome steel or a chrome nickel alloy. Since these alloys are familiar in the art they need not be described in detail. Because of the use of these alloys the gate structures are inherently quite durable. Furthermore, since the gates are composed of relatively small sections, it is 10 obvious that only a relatively small degree of distortion may be imparted to any given section. For this reason even though a particular section may be distorted, the distortion to the structure as a whole is relatively slight.

In case any particular unit of the structure 15 becomes unduly defective it may readily be removed and replaced by a new unit. In normal operation of the furnace it will be apparent that the lower unit 42 is exposed to the highest temperatures and to the strongest flow of oxidizing gases, and for that reason it needs to be replaced more frequently than any of the other units. The construction constituting the subject matter of the present invention is particularly effective where replacement of this section 20 or the sections adjacent thereto is necessary. This is true because, to replace these bottom sections it is only necessary to remove the required pin 50 or bolt 56 and then to slide the defective section longitudinally from the groove 25 of the adjacent section. The sections above the one to be removed are not disturbed. To effect this longitudinal movement of the defective section it is merely necessary to remove the valve structure from the guides 12 or, if desired, a 30 suitable opening in the side of the furnace flue may be provided thus permitting removal of the section without complete removal of the entire valve.

Although I have described only the preferred 35 forms of the invention it is to be understood that these forms are merely illustrative and that various modifications may be made therein without departing from the spirit of the invention or from the scope of the appended claims.

I claim:

1. A valve structure for flues comprising guides disposed in the side walls of the flue at an angle with respect to the vertical and a gate reciprocable within the guides, said gate being formed of independently movable sections, the sections having flanges formed about the margins thereof, the flanges at the ends of each section being adapted to rest against the lower wall of the guides in order to provide seals about the sides of the gate.

2. A valve structure for flues comprising guides disposed transversely of the flue and at an angle with respect to the vertical, a gate composed of a plurality of sections disposed transversely of and slidable within the guides, certain of said sections each having a T-shaped flange formed along a longitudinal edge thereof, certain of said sections each having opposed flanges formed along a longitudinal edge thereof and directed outwardly and then inwardly to define a T-shaped groove adapted to slidably receive the correspondingly shaped flange of an adjoining section, and opposed flanges on the ends of the sections of the same cross-sectional width as 60 said first named opposed flanges.

EDGAR D. FLINTERMANN.
